(57) **CLAIM**

The ornamental design for a figurine, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a figurine, showing my new design; FIG. 2 is front and right perspective view thereof;

FIG. 3 is a left side view thereof;

FIG. 4 is a right side view thereof;

FIG. 5 is a top view thereof;

FIG. 6 is a bottom view thereof;

FIG. 7 is a rear view thereof;

FIG. 8 is a top, front and right perspective view thereof; and,

FIG. 9 is a bottom, front and left perspective view thereof.

**1 Claim, 9 Drawing Sheets
(9 of 9 Drawing Sheet(s) Filed in Color)**
